UNITED STATES PATENT OFFICE.

CARL SCHOENERT, OF NEWARK, NEW JERSEY.

THREAD-CUTTING TAP.

1,232,099.

Specification of Letters Patent. Patented July 3, 1917.

Application filed January 18, 1917. Serial No. 143,169.

To all whom it may concern:

Be it known that I, CARL SCHOENERT, a citizen of the United States, residing at Newark, in the county of Essex and State 5 of New Jersey, have invented certain new and useful Improvements on Thread-Cutting Taps, of which the following is a specification.

The present invention relates to taps for 10 cutting female threads. Taps as usually constructed are solid and are provided with a number of lengthwise slots extending to or beyond the region of the thread, and these slots become rapidly clogged with cuttings, 15 and in order to prevent the thread being marred by the cuttings the tap must be screwed out from time to time and cleaned, and to make a satisfactory thread considerable time and trouble is required, particu- 20 larly in the case of tapping holes of a large diameter. Also it is frequently necessary to make use of a series of taps of such ordinary construction in multiple, one after another, in order to obtain a sharp and properly de- 25 fined thread, especially when tapping holes of comparatively large diameter. When such solid taps break off in use, as they frequently do, their removal is a matter of ex- 30 treme difficulty.

According to the present invention a tap 35 is provided having a hollowed out central portion or bore whereby the tap is strengthened, and it also becomes possible to readily remove it, if it should be broken off, by 40 means of suitable tools introduced into the bore of the broken tap.

Another object of the invention consists in 45 the provision of means for leading and directing the cuttings to the hollow bore so that they readily pass into the bore or drop to the bottom of the hole and do not clog up the cutting surfaces. The bore may be utilized to supply lubricant.

Another object of the invention consists in 50 the provision of a tap cut away at or along one side only, thus dispensing with the usual plurality of separate slots and obtaining an improved cutting surface and facilitating the entering of the tap into the hole which 55 is to be threaded. When the central bore is provided in taps in accordance with my invention, the same may be obtained in any suitable way, as by drilling solid stock or by making use of hollow taps from which the edge may be constructed, or in other ways. The cutting away of the bore in at

least a part of the tap does not extend as far as the center thereof, so that the fitting of the tap in place in the opening is not interfered with and the threads obtain a 60 good cutting action against the material on the sides of the opening of the bore. The cutting away may be all along one side or may be of other forms, as, for example, the cut away portion of the tap may be of spiral 65 form or various other forms, but is preferably so carried out as to bring each cutting tooth somewhat out of line with the preceding cutting tooth or thread, whereby the cutting action advances or retreats substantially on an incline, thereby greatly reducing the danger of tap breakage and giving greater ease of operation. 70

With the foregoing and related objects in view, my invention consists in the features 75 of construction and improvement herein set forth and claimed.

In the accompanying drawings I have 80 illustrated, for the purpose of making my invention clearly understood and not for the purpose of limitation, however, three forms of taps in which my invention may be embodied. In the said drawings, Figure 1 is a side view of one form of tap embodying my invention. Fig. 2 is another side 85 view of the same tap taken at right angles to Fig. 1. Fig. 3 is a cross-sectional view taken on the line 3—3, Fig. 1. Fig. 4 is a side view of another form of tap embodying my invention. Fig. 5 is a second side view 90 of the tap shown in Fig. 4 and taken at right angles thereto. Fig. 6 is a side view of a third form of tap embodying my invention, and Fig. 7 is a second side view of the tap shown in Fig. 6 and taken at right angles 95 thereto.

Numerals 10 designate the shank of the tap and 11 the customary square head by means of which power may be applied to turn the tap, it being understood, of course, 100 that other means for rotating the tap may be resorted to. 12 indicates the hollow bore of the tap and 13 threads formed thereon which, as is usual, are shortened or cut off at the entering end of the tap. In the form shown in Figs. 1 and 2 a substantially spiral cut away portion 14 is provided, forming an opening of substantially spiral character along one side of the tap and communicating with the hollow interior 12. The cutting edges 15, if desired, may be made progressively sharper toward the top of the tap, 105

or, in other words, the under cut may be increased, so that the cut is finished with the sharpest pointed teeth and is begun with teeth which are relatively dull or not so sharply pointed.

- In the tap shown in Figs. 1 and 3, when cutting right hand threads the cutting edge is represented at 15, and this edge is cut back at an angle, as indicated at 16, so as to 10 provide a sharp under cut cutting edge for the points or teeth of the thread 13 whereby an efficient cutting action is obtained. The opposite edge 17 is shown as projecting somewhat on the interior instead of being 15 under cut, but the precise form of this edge is not important, except that it is preferably so designed as to give as great strength as possible. This substantially spiral cut in the die may be readily formed, as, for example, by a milling machine.

In Figs. 4 and 5 the tap 20 has a central bore 21, and the cut away portion 22 thereof is all on one side. In this form the cut away 22 is provided by forming substantially 25 scalloped portions comprising alternate projecting parts 23 and recessed parts 24, the scallops extending substantially directly across the tap at right angles to the longitudinal axis thereof, and the cutting 30 away or scalloping of the tap not being extended in at least a portion of its length entirely through the median line thereof, whereby the proper location of the tap in the hole to be threaded is not interfered 35 with. In this way the cutting edge gradually advances and retreats as the tap cuts deeper, so that the cutting action is always more or less on an incline.

In Figs. 6 and 7 the tap 30 has a bore 31, 40 and the tap of these figures is similar to that of Figs. 4 and 5, except that the scalloped portions 32 are formed at an angle to the longitudinal axis of the tap other than a right angle. This precise angle may, of course, vary from that shown.

The operation of a tap in accordance with my invention will be readily understood from the foregoing. Being introduced in a hole to be threaded in the ordinary way, 50 it may be readily screwed down, and with one passage a sharply defined thread obtained, the cuttings dropping out as fast as they are formed and not interfering with the cutting action, very little power being 55 required for making the cut, the use of multiple taps to secure a sharp thread is no

longer requisite, and the taps so constructed are very strong and will scarcely ever break off, and if they should it is readily possible to remove the same by means of a proper 60 tool which may be inserted in the central bore.

It is to be understood that the forms illustrated are for the purpose of affording a clear understanding of my invention only, 65 and that I am not to be confined to such specific form or forms, but that numerous changes therein and departures therefrom may be resorted to within the scope of my claims and without departing from or sacrificing any of the advantages of my invention. 70

What is claimed is:

1. A tap having a hollow bore and provided with an elongated cut away part 75 extending from the bore to the exterior of the tap and providing cutting teeth at one edge of the cut away part.

2. A thread tap having a hollow bore and a cut away part extending throughout the 80 length of the threaded portion.

3. A tap having a threaded exterior wall, the threads being continuous except on one side of the tap where the material thereof is cut away, the cut away extending inwardly and including the longitudinal axis 85 of the tap.

4. A tap provided with an exterior threaded cutting surface and with a hollow interior bore, the material of the tap being 90 cut away from the bore to the exterior thereof along substantially a spiral line.

5. In a tap, a threaded exterior cutting surface, an interior hollow bore, said tap being cut away from the bore to its exterior 95 and providing forwardly inclined sharp cutting teeth on the cutting edge of the tap.

6. In a tap, a threaded exterior cutting surface, an interior hollow bore extending into the shank beyond the threaded surface, 100 said tap being cut away from the bore to its exterior surface, said cut away being on an angle on the cutting side of the tap whereby the cutting teeth have sharp penetrating points.

7. A tap provided with an outer threaded surface and a hollow bore, and being cut away to the bore on one side, the cut away part providing cutting teeth arranged at an angle to the longitudinal axis of the tap. 110

In testimony whereof I affix my signature.

CARL SCHOENERT.
